HIGH-FREQUENCY GLUE CURING PRESS

Harrell Renn, Albany, Oreg., assignor to M and M
Wood Working Company, Portland, Oreg., a
corporation of Oregon

Application August 28, 1950, Serial No. 181,776

9 Claims. (Cl. 144—281)

1

This invention relates to an improved apparatus for applying heat and pressure to a glued joint, as, for example, in the patching of plywood where defects have been removed.

In the heat setting of plywood patches by the use of high frequency electrical fields, considerable difficulty has been encountered in developing a satisfactory electrode carrying pressure member to hold the patch in place and establish the necessary high frequency dielectric field to heat-set the glue on the patch. It has not been possible to find a dielectric material to insulate the electrodes at the work engaging face of the pressure member which will give satisfactory service under the pressure, electrical and temperature conditions which are necessary to set the patch quickly. It is found that dielectric material on the work engaging face becomes heated to a rather high degree when glue is squeezed out of the joint around the edges of the patch in contact with the dielectric material. Such glue, together with dust and other foreign material, forms a conducting film on the face of the dielectric member which is heated by the high frequency field in the same manner as the glue line under the patch. The resulting local heating on the surface of the pressure member not only deteriorates the dielectric material and materially shortens its life, but it also reduces the heating effect in the glue line under the patch and is wasteful of electrical energy. Also, a flash is liable to occur which forms a carbon path for the electrical current on the surface of the insulating material. This has to be cleaned off before the head will operate satisfactorily. If enough insulating material is placed between the glue line and the metal feet of the head to eliminate this flashing, the power available to the glue line is decreased and the time necessary to set the patch is increased.

The general object of the present invention is, therefore, to provide an improved pressure member for a glue curing press, in which the necessary solid dielectric material for insulating the electrodes does not come into contact with the work surface and any glue or dust that might be on such surface. A more particular object is to provide a pressure member having bare metal electrodes to contact the work directly, wherein the electrodes are separated by air gaps at the work engaging face, rather than by solid dielectric material.

Further objects are to provide an improved form of electrode pressure member particularly adapted for the setting of long rectangular

2

patches, and to provide an improved mounting arrangement and actuating mechanism for a high frequency patch press.

The characteristic feature of the invention is a pressure member having the necessary insulating material for the electrodes spaced from the work surface, and having a pressure face consisting of bare electrode elements which contact the work surface directly and apply the necessary mechanical pressure to the top of the patch. The electrodes preferably comprise parallel feet of different polarity extending across the patch to establish a plurality of dielectric fields over small sub-areas covering the patch. In the case of a rectangular patch having square ends, it is preferred to direct the work engaging feet of the electrodes at an angle of 45 degrees with respect to the sides of the patch to insure uniform application of pressure and heat at both ends of the patch.

The invention will be better understood and still further objects and advantages will become apparent from the following description of the different embodiments illustrated in the accompanying drawings. Various changes may be made in the construction and arrangement of parts and certain features may be used without others without departing from the spirit of the invention as defined in the appended claims, it being understood that the drawings are intended merely to illustrate the principles of the invention and not to limit the invention.

In the drawings:

Figure 1 is a side elevation view, with parts in section, showing a plywood patch press embodying the principles of the invention;

Figure 2 is a view taken on the line 2—2 of Figure 1;

Figure 3 is a perspective view, partly in section, of a plywood panel containing a sled patch;

Figure 4 is an enlarged perspective view of the electrodes shown in Figure 1;

Figure 5 is a sectional plan view of a modification having diagonal electrode feet;

Figure 6 is a top plan view of another modification, with parts broken away, showing a different electrode arrangement; and

Figure 7 is an end elevation view of the embodiment shown in Figure 6.

Referring now to the general view in Figure 1, the numeral 10 designates a table for supporting a plywood panel W having a patch P to be glued in place. The numerals 11 and 11a designate electrodes of opposite polarity which comprise a heating and pressure member for furnishing the

heat and pressure necessary to glue the patch P to the panel. The two electrodes 11 and 11a are connected at one end by short flexible leads 12 and 13 to coaxial conductors 14 and 15 which extend back to a suitable high frequency generator G. The numeral 16 designates a small inductance mounted on the opposite ends of the electrodes to tune the circuit. This inductance may not be required if the electrical properties of the head are such as to match the load to the high frequency generator.

The electrodes 11 and 11a are secured by screws 17 to the under side of a heavy rigid block of dielectric insulating material 20. The heads of screws 17 are conventionalized in Figure 1, but it is understood that in practice the screw heads are either flat or rounded, and are countersunk so as to be substantially flush with the electrode surface to avoid projecting corners which would produce corona and brush discharge effects. The block of dielectric material 20 is secured to a metallic plate 21 by means of screws 22 which are positioned remotely from the nearest screws 17. Plate 21 is mounted on the lower end of a plunger 23 which is carried by a piston rod 24 extending from a piston in a double acting air cylinder 25.

Numerals 26 and 27 indicate air supply and exhaust pipes for opposite ends of the cylinder 25. These pipes are connected through conventional reversing valve mechanism with a suitable compressed air supply for lowering and raising the piston rod. When compressed air is admitted to the cylinder above the piston through pipe 26 and the air under the piston is allowed to exhaust through pipe 27, the piston is driven downwardly in the cylinder with considerable force. When compressed air is admitted through pipe 27 to the cylinder beneath the piston and pipe 26 is opened to exhaust, the piston is raised in the cylinder and the various parts of the apparatus assume the positions shown.

The upper end of plunger 23 is mounted for sliding movement in a bore 28 in the piston rod 24. The lower end of the piston rod is equipped with a flange 29 having studs 31 with adjustable stop nuts 30 to limit the movement of plunger 23 relative to the piston rod. A stop plate 32 on plunger 23 has holes loosely fitting the studs 31 whereby plunger 23 is lifted by nuts 30 on the upward stroke of piston 24 and pressed downwardly by flange 29 on the downward stroke of the piston. The nuts 30 are backed off on the studs 31 to a greater distance from the flange 29 than the thickness of plate 32 to allow a certain amount of lost motion. Plunger 23 is urged downwardly relative to the piston rod by spring 33.

Also mounted on flange 29 is a bracket 34 carrying a switch 35 to control the energization of the electrodes 11 and 11a. Switch 35 has an actuating button 36 positioned to be depressed by the plate 32 when the flange 29 engages said plate. The switch is normally open to deenergize the electrodes when the parts are in non-working position as shown in Figure 1. Air pressure in pipe 27 then holds the piston rod 24 in its upper position supporting the electrodes at a distance above the top of table 10 by the engagement of nuts 30 with the underside of plate 32 and button 36 is not engaged by the plate 32. With the pressure member thus raised, a panel W having the patch P is moved across the table 10 to a position placing the patch under the

electrodes of the pressure member, as shown. It is understood that the patch P has previously been coated with thermosetting glue on its underside and placed in position in a defect removal opening or recess in the top face of the panel which exactly fits the patch.

The patching machine is equipped to perform automatically all the operations necessary to secure the patch after it has been placed in position as shown in Figure 1, but it will be understood that only those parts of the machine necessary to an understanding of the present invention are illustrated. The machine is placed in operation by admitting compressed air to the pipe 26 and opening the pipe 27 to exhaust, thereby causing the piston rod 24 to be driven downwardly, lowering the electrodes toward the work. As soon as the electrodes rest upon the work, flange 29 moves downwardly against stop plate 32, causing switch button 36 to engage this plate and close switch 35, to energize the electrodes. Thus, the heating cycle is started concurrently with the application of pressure to the patch.

It will be understood by persons skilled in the art that when the electrodes 11 and 11a are thus energized, high frequency dielectric fields are set up between the electrodes to produce stray field heating of the thermosetting glue on the underside of the patch. The glue is heated more quickly than the surrounding wood, and, with the application of sufficient electrical energy, it is set in a matter of a few seconds while the patch is held firmly in place by the electrodes on the pressure member.

The operation may be terminated manually, but preferably by a suitable time control mechanism (not shown) connected with the mentioned air valve to reverse the connections to pipes 26 and 27. When air pressure is admitted to pipe 27 and pipe 26 is opened to exhaust, piston rod 24 is raised. As the piston rod starts to move upwardly flange 29 draws away from plate 32 to release the switch button 36 and allow switch 35 to open, deenergizing the electrodes and terminating the heating cycle. Nuts 30 engage the underside of the plate 32 to raise the pressure member back to its Figure 1 position so that the patched panel can be removed.

Figure 1 also does not show the usual movable guard cage around the pressure member to prevent the operator from coming into contact with the electrical conductors while they are energized.

Figure 3 is an enlarged broken away view illustrating a sled patch applied to a plywood panel to eliminate a defect in the top veneer of the panel. The panel is prepared for patching by routing out the defect in the face veneer 41 of the three-ply panel W which comprises the three sheets of veneer 41, 42 and 43. The routing operation to remove the defect is carried down to the glue line between veneers 41 and 42, and is confined to an outline corresponding to the size and shape of the prepared patch P. The veneers in a plywood panel are frequently of different thickness, the face veneer 41 being the thinnest, which places the glue line on the patch relatively close to the top surface which is engaged by the electrodes and in an effective position for stray field heating. In boards and lumber the routing is carried down to a depth equal to the thickness of the patch to be applied.

The electrode pressure member of the present invention may be used with any form of conventional patch such as a circular patch, an oval

patch, an elongated round end patch, or a boat-shaped patch, but the sled patch illustrated in Figure 3 is particularly well suited for patching the face sheets of plywood panels. The sled patch *P* has parallel sides 44 running with the grain, and square cut end lines 45. The name "sled patch" derives from the fact that the ends taper in thickness in a curve 46 which is tangent to the bottom surface of the patch and substantially intersects the top surface of the patch at the end line 45. Thus, the glue line on the bottom of the patch is brought to the surface of the panel at both ends of the patch in long sweeping curves which correspond in general to the curvature of the stray field beneath the electrodes, so that the stray fields in the glue line at the ends of the patch become practically a part of the main field, thereby increasing the heating effect in the glue and reducing the heating of the wood. The side edges 44 of the patch are also inclined but at a much steeper angle than the end surfaces 46 and are flat, edge grain surfaces. End surfaces 46 have a maximum of flat grain and a minimum of end grain, which enhances the strength of the bond at the ends of the patch.

The electrodes 11 and 11a, shown in perspective in Figure 4, are identical castings made from a non-corrodible metal such as bronze. Each electrode has a top bar 51 rigidly secured to the flat underside of the insulating block 20 by means of screws 17. Depending from the bar 51 are a plurality of vertical legs 52 having parallel feet 53 extending horizontally in a lateral direction. The feet 53 have flat work engaging surfaces 55 on their undersides disposed in a common plane parallel with the underside of insulating block 20. The two electrodes 11 and 11a are mounted on the block 20 with the feet 53 oppositely directed and equally spaced to provide a series of island work engaging surfaces at a considerable distance from the dielectric material. The bars 51 and legs 52 of the two electrodes are considerably farther apart than the spacing of the feet 53, and so, when the electrodes are connected to a suitable source of high frequency electrical energy, a strong alternating dielectric field is established between the feet 53 substantially in the plane of the work engaging surfaces 55, and the stray field through the glue line on the bottom of a thin veneer patch is relatively close to the plane of surfaces 55 when these surfaces are pressed down upon the top of the patch.

The glue spread on the patch should be controlled so that a minimum of excess glue will be squeezed out around the margin of the patch, but, even if some of the wet glue does come into contact with the bare electrodes, it does not interfere materially with the heating of the main film of glue on the bottom of the patch. Such glue as may be squeezed out does not come in contact with the dielectric block 20, and ample spacing and ventilation are provided between the block 20 and the work surface so that in any event the dielectric material does not become heated from the work. Under the worst conditions, some wet glue along an edge of the patch, or a smear of wet glue on top of the work surface, might bridge the gap between a pair of the electrode feet to cause a momentary flash-over, but when this happens the head can be raised, the excess burnt glue scraped off the panel and the head again lowered to continue the heating without harming the block 20 to any extent.

Figure 5 shows a sectional view of a modified

electrode arrangement, taken on a horizontal plane intermediate between the work engaging surfaces of the electrodes and the dielectric block on which they are mounted. In this embodiment, the two electrodes 60 and 61 take the same form as the electrodes 11 and 11a in Figure 4 except that the legs 62 and feet 63 are directed at an angle of approximately 45 degrees to the longitudinal direction of the patch *P* and bars 51. The angular disposition of the feet 63 in Figure 5 insures more uniform application of heat and pressure at the ends of a rectangular patch than would necessarily be obtained with the embodiment shown in Figure 4 where the two ends of the patch might be spaced differently from the nearest electrode foot. In Figure 5 it will be seen that at least one of the feet 63 will always lie across an end line 45 to hold it down flat without careful positioning of the panel under the tool.

The types of electrode pressure member shown in Figures 4 and 5 are used on patches considerably shorter than the pressure member as exemplified by the patch *P* in Figure 5, and also on long patches which require two or more applications of the pressure member to treat the whole length of the patch. When the patch is longer than the pressure member, the pressure member is first applied to one end of the patch and then the panel is shifted longitudinally of the patch and the pressure member applied again, over the other end of the patch. This style of patch is particularly convenient in view of the fact that most defects in wood extend along the grain in such a manner that a long defect does not require any wider patch than a small defect. The sled type patch and the present electrode arrangement thus allow the patches to be made in different lengths, all having the same width, so that the largest and smallest patches may be set with the same equipment. Heretofore, the conventional shapes of the patches have required different heat and pressure tools for different sizes of patches.

Figures 6 and 7 show an electrode arrangement for use with a three wire push-pull circuit or by proper connections used in the conventional two wire or coaxial line circuit. The two electrodes 71 are connected to one circuit wire, the electrodes 72 to another circuit wire, and the electrodes 73 to the third, or neutral, circuit conductor which may be grounded to the pressure member of the machine. For use on the conventional two wire circuit or coaxial line circuit the four electrodes 71 and 72 are connected electrically and connected to one line and the electrodes 73 are connected electrically and connected to the other line.

In this embodiment, the four electrodes 71 and 72 are mounted in a rigid dielectric member 75, and the intervening electrodes 73 are mounted in a top plate 76 which is secured to the piston rod of a fluid pressure cylinder to apply the necessary pressure to all the electrodes. Electrodes 73 are T-shaped and have vertical legs 77 secured in the plate 76. In an installation and circuit where it is feasible to ground the third wire to the piston rod or plunger 23, the plate 76 may be a metal plate in electrical contact with plate 21, but the plate 76 may also be an insulating block similar to the dielectric block 20 in Figures 1 and 4, the upright legs 77 of the electrode 73 then being connected together by a suitable bus bar or other common conductor.

The lower extremities of all the electrodes in Figures 6 and 7 are disposed in a common hori-

zontal plane to present the effect of a flat pressure face in engagement with the work surface, as shown. Each electrode thereby presents an island work engaging surface against the patch B, remote from the dielectric supporting material. The work surface, electrodes and dielectric material 75 are well ventilated as in the Figure 4 and Figure 5 embodiments.

The work engaging feet of the electrodes in Figure 6 are of different lengths to cover an oval area slightly larger than the conventional boat-shaped patch B, but the same general electrode arrangement may obviously be adapted to circular patches, round ended long patches, and the present sled patch P. It will also be apparent to persons skilled in the art that the electrodes may be turned to diagonal positions as in Figure 5 and that they may be limited to three in number and disposed longitudinally instead of transversely of the patch, if desired.

Thus, the different embodiments illustrate a variety of bare electrode patch pressing tools wherein the electrodes themselves have air separated island work engaging portions to create the dielectric high frequency heating field and to hold the patch in place while the glue under the patch is being heated to its thermosetting temperature. In each embodiment, the necessary dielectric support and pressure applying member is spaced above the work surface where it will not become heated nor smeared with glue from contact with the work. There is ample ventilation above the work surface to cool the electrodes and dielectric member and provide for the escape of steam from the wood and from the moisture in the wet glue. Still other electrode arrangements having these features and advantages will occur to persons skilled in the art, and all such additional modifications within the scope of the appended claims are included in the invention. The heat and pressure applying tool engages only the work surface which is to be patched and so relatively thick plywood and lumber may be treated with the same efficiency as conventional thicknesses of plywood.

Having now described my invention and in what manner the same may be used, what I claim as new and desire to protect by Letters Patent is:

1. In a high frequency glue curing press, a pressure member having work engaging electrodes of different polarity adapted to be connected with a high frequency generator, a member for moving said pressure member toward and away from a work piece, a lost motion connection between said two members, and a switch controlling the energization of said electrodes mounted on one of said members and engageable with the other member for actuation by relative movement of the two members while said pressure member is in engagement with the work piece.

2. In a high frequency glue curing press for pressing a patch into a prepared recess in one surface of a wood panel and the like, a plurality of electrodes of different polarity having spaced parallel pressure feet constituting a rigid discontinuous pressure face arranged to engage the patch and extend over the edges thereof in contact with exposed glue lines at said edges on said one surface of the panel, and a dielectric supporting and pressure applying member for said electrodes connected therewith in spaced relation with said pressure feet, said pressure feet being otherwise separated from each other and

from said supporting member by ventilating air gaps communicating with atmosphere.

3. In a high frequency glue curing press for pressing a patch into a prepared recess in one surface of a wood panel and the like wherein said patch and recess have glue lines exposed on said surface around the edges of the patch, a table for supporting said panel with said one surface uppermost, a dielectric member mounted for movement toward and away from said surface, electrodes of different polarity mounted on said member, and work engaging pressure feet on said electrodes separated from each other and from said dielectric member by air gaps.

15 4. In a high frequency glue curing press for pressing a patch into a prepared opening in a sheet and wood veneer and the like whereby glue lines around the edges of the patch are exposed on the face of the sheet, a dielectric block, electrodes of different polarity mounted on said block, and pressure feet on said electrodes having legs extending outwardly from said block, said pressure feet being otherwise separated from each other and from said block by ventilating and insulating air gaps and said feet being arranged to engage the surface of said patch and extend over said exposed glue lines to press all parts of the patch firmly in place.

20 5. In a high frequency wood patch press, a stray field type heating and pressing member adapted to engage the face surface of a veneer patch and the like and extend over the edges of the patch in contact with exposed glue lines at the edges of the patch, said member comprising a dielectric block and a pair of electrodes of different polarity, said electrodes having elongated base portions mounted on said block, and oppositely directed interdigital work engaging pressure feet extending outwardly from said base portions of the electrodes but otherwise separated from each other and from said block by ventilating and insulating air gaps.

25 6. In a high frequency wood patch press, a stray field type heating and pressing member adapted to engage the face surface of a veneer patch and the like and extend over all the edges of the patch in contact with exposed glue lines at the edges of the patch, said member comprising a dielectric block and a pair of electrodes of different polarity, said electrodes having elongated base portions mounted on said block in parallel relation, and oppositely directed parallel interdigital work engaging pressure feet offset outwardly from said base portions of the electrodes and extending at oblique angles relative thereto, said pressure feet being otherwise separated from each other and from said block by ventilating and insulating air gaps.

30 7. A high frequency heating and pressing unit for relatively stationary application to one surface of a work piece such as wood veneer and the like comprising, a rigid dielectric member relatively movable toward and away from said surface, rigid electrodes of different polarity mounted on said member, and rigid feet on said electrodes outstanding from said dielectric member and arranged to constitute a discontinuous pressure face to engage and apply substantial pressure to said one surface of the work piece in a heating cycle, said electrode feet being separated from each other and from said dielectric member by ventilating air gaps communicating with atmosphere.

35 8. A high frequency glue curing press for pressing a patch into a prepared opening in a sheet

of wood veneer and the like whereby glue lines around the edges of the patch are exposed on the face of the sheet comprising, a table for supporting said sheet with said face uppermost, a rigid dielectric member, a fluid pressure operated unit connected with said dielectric member for moving said dielectric member relatively toward and away from said table, electrodes of different polarity mounted on said dielectric member, and rigid outstanding work engaging 10 pressure feet on said electrodes separated from each other and from said dielectric member by ventilating air gaps communicating with atmosphere.

9. A high frequency glue curing press for 15 pressing a patch into a prepared opening in a sheet of wood veneer and the like whereby glue lines around the edges of the patch are exposed on the face of the sheet comprising, a table for supporting said sheet with said face uppermost, 20 a pressure applying member having a rigid dielectric element, a fluid pressure operated member for moving said pressure applying member and dielectric element relatively toward and away from said table, electrodes of different polarity mounted on said dielectric element, work

5

10

engaging pressure feet on said electrodes separated from each other and from said dielectric element by air gaps communicating with atmosphere, a lost motion connection between said two members, and a switch controlling the energization of said electrodes mounted on one of said members and engageable with the other member for actuation by relative movement of the two members while said pressure feet are in engagement with the sheet.
